UNITED STATES PATENT OFFICE.

CHARLES S. SHARP, OF AUBURN, NEW YORK, ASSIGNOR TO THE D. M. OSBORNE & COMPANY, OF SAME PLACE.

KNOT-TYING DEVICE FOR GRAIN-BINDERS.

SPECIFICATION forming part of Letters Patent No. 609,522, dated August 23, 1898.

Application filed January 11, 1897. Serial No. 618,720. (No model.)

To all whom it may concern:

Be it known that I, CHARLES S. SHARP, of Auburn, in the county of Cayuga and State of New York, have invented an Improvement in 5 Knot-Tying Devices for Grain-Binders, of which the following description, in connection with the accompanying drawings, is a specification, like letters on the drawings representing like parts.

10 This invention relates to knot-tying devices for grain-binders, and has for its object to improve the construction of the same, to the end that the cord while yet held in a good and sufficient manner by the cord-holder may more 15 easily render to the knot-tying bill during the knot-tying operation; and my improvement is of particular importance when irregular or lumpy cord is used, as such cord may likewise easily render from the cord-holder during 20 the knot-tying operation without undue strain upon the parts and without binding or cutting the cord.

Prior to this invention the cord-holder has usually been so disposed as to face the knot-tying bill, and the cord held by said cord-holder is withdrawn more or less, as required, 25 during the tying operation; but with the parts so disposed the strain or pull upon the cord is at or nearly at right angles to the movement of the cord-holding plate away from the cord-holding disk when yielding for the delivery of the cord, and by reason of such right-angular or lateral strain upon said cord-holding plate it will bind more or less and not 30 easily yield, and in case irregular or lumpy cord is drawn into the cord-holder the excessive pull or strain required to withdraw it only increases this binding action and lessens the ease or freedom of motion of said cord-holding plate, and as a consequence the cord will 35 break or its delivery will be so retarded as to cause trouble.

In accordance with this invention I have set the cord-holder edgewise to the knot-tying 40 bill by arranging the spindles of both the cord-holding disk and the knot-tying bill so as to turn on axes radial to the main operating-shaft of the knotter, and have pivoted the cord-holding plate, which co-operates with said 45 cord-holding disk, to the frame at one side of said disk, and have provided a spring which

bears upon said plate, so that it is free to yield toward and from the cord-holding disk, and said yielding cord-holding plate is located on that side of said cord-holding disk 55 adjacent the knot-tying bill, so that the cord which passes from the cord-holder passes directly over said plate to the knot-tying bill substantially at right angles to the axis of the spindles, and with the parts so disposed any 60 strain on said cord sufficient to overcome the pressure of the spring will cause said plate to yield or turn on its pivot or move toward the knot-tying bill, which is in a direction corresponding to the strain or pull upon the cord, 65 and hence in a direction to most easily turn said plate.

The cord-holding plate embraces a segmental portion of the disk between the spindle of said disk and the knot-tying bill, and that portion of the edge of said plate along which the cord runs as the disk turns lies substantially parallel to the knotter-shaft, so that as said disk is turned no cord whatever will render toward the bill and all cord used in 75 forming the knot will be drawn from between the plate and disk which holds it.

Figure 1 shows a rear elevation of a knot-tying device embodying this invention; Fig. 2, a detail of the cord-holder; Fig. 3, a detail 80 showing the relative positions of the parts and cord while the bundle is being formed; Fig. 4, a similar view showing the cord in position to be tied; Fig. 5, a similar detail showing the knot half formed and cord fully in 85 holder, and Fig. 6 shows the knot prior to stripping it from the knot-tying bill.

The knot-tying shaft A and cam A' secured to it, which is constructed and arranged to serve as an actuator for the co-operative parts, 90 together with the frame and the spindles a b, having their bearings in said frame radial to the axis of said shaft A; the knot-tying bill a', secured to the radial spindle a, and the cord-holding disk b', secured to the radial 95 spindle b, are all of usual or suitable construction, and said parts being disposed with the spindles a b radial to the axis of the shaft A it will be seen that the cord-holding disk b' is set edgewise to the knot-tying bill. The 100 cord-holding plate c, curved longitudinally and having a groove of suitable depth and

width formed along one edge, is pivoted to the frame at c' and is held pressed into engagement with the cord-holding disk b' by means of a strong flat spring c^2 , which is attached 5 to the frame. This pivoted cord-holding plate c is located upon that side of the cord-holding disk adjacent the knot-tying bill, so that its own movement on its pivot toward and from the cord-holding disk is toward and from said 10 knot-tying bill.

The cord-holding plate c embraces a segmental portion of the disk between the spindle of said disk and the knot-tying bill, and that portion of the edge of said plate along 15 which the cord runs as the disk turns lies substantially parallel to the knotter-shaft or at right angles to a plane intersecting the spindles of the knot-tying bill and disk. The cord d , which is delivered from the cord- 20 holder, (which consists of the cord-holding disk and cord-holding plate,) passes directly over the plate c and thence to the knot-tying bill, being drawn substantially at right angles to the spindles, and any pull or strain 25 upon this cord will cause the cord-holding plate to turn on its pivot or yield in a direction toward the knot-tying bill, in which direction it can most easily be turned without binding. With the parts disposed as herein 30 shown, if irregular or lumpy cord should be drawn into the cord-holder it will render freely without binding or straining the parts, as the cord-holding plate is free to yield in a direction corresponding to the pull or strain 35 upon the cord.

I am aware that a cord-holder has heretofore been set edgewise to the knot-tying bill, so that the cord delivered from said cord- 40 holder would pass over the cord-holding plate to the knot-tying bill in a direction substantially at right angles to the axis of the cord- holding disk; but the parts were so constructed and arranged that the cord was rendered 45 to the knot-tying bill by the turning of the disk, whereas in the present case the cord is not rendered by the turning of the disk, but is drawn from between the disk and plate during the knot-tying operation by the knot-tying bill.

50 The spring c^2 , pressing upon the cord-holding plate, is broadened at its lower end, and its broadened portion is formed with a curved upper edge, which serves as a guide for the cord. After the knot is tied and the cord severed if the knife-arm should not return to its 55 normal position quickly there is liability of the cord placed by the needle for the next bundle being carried under the knotter by the back of the knife-blade; but by the provision 60 thus made the cord is held upon the upper part of the curved guide until the knife-arm swings back into place, when the pressure of the accumulating grain on the cord causes it to slip down over the end of the 65 spring, drawing it with certainty within the travel of a tooth of the disk.

In Fig. 6 the needle is supposed to be at the full limit of its forward movement, the knotter-bill is in position to have the knot stripped from it, and the knife-carrying arm just ready 70 to give the swing that will result in the cutting of the twine. In said figure the twine which passes under the disk b' is from the eye of the needle, and it is carried to a point where it will be caught by the notched disk 75 and spring-holder when the needle returns to its normal position. When the knife-arm swings so that the knife cuts the cord, the part p thereof moves directly across the path 80 of the needle and holds up the twine until the knife-arm swings back into position, when the twine drops down into the position shown in the loop of the knife-arm.

I claim—

1. In a knot-tying device for grain-binders, 85 a knot-tying bill and a cord-holding disk, turning on axes radial to the knotter-shaft, a movable cord-holding plate embracing a segmental portion of said disk between the spindle of said disk and the knot-tying bill, 90 a spring bearing upon it, that portion of the edge of said plate along which the cord runs, as the disk turns, occupying a position substantially parallel to the knotter-shaft, whereby the cord used in making a knot is 95 pulled from the cord-holder by the knot-tying bill without rotating the holding-disk, substantially as described.

2. In a knot-tying device for grain-binders, 100 a knot-tying bill and a cord-holding disk, turning on axes radial to the knotter-shaft, and a movable cord-holding plate embracing a segmental portion of said disk between the spindle of said disk and the knot-tying bill, 105 a spring bearing upon it, the edge of said plate along which the cord runs as the disk turns and over which the cord is drawn by the bill in forming the knot, occupying a position substantially at right angles to a line intersecting the spindles of said disk and bill, substantially as described.

3. In a knot-tying device for grain-binders, 110 a knot-tying bill and a cord-holding disk, turning on axes radial to the knotter-shaft, and a movable cord-holding plate embracing 115 a segmental portion of said disk between the spindle of said disk and the knot-tying bill, a spring bearing upon it having a curved guide for the cord near the cord-holding plate, the edge of said plate along which the cord runs 120 as the disk turns and over which the cord is drawn by the bill in forming the knot, occupying a position substantially at right angles to a line intersecting the spindles of said disk and bill, substantially as described.

In testimony whereof I have signed my name to this specification in the presence of two subscribing witnesses.

CHARLES S. SHARP.
